(57) **CLAIM**

The ornamental design for a pet treat, as shown and described.

DESCRIPTION

FIG. 1 is a perspective view of a pet treat showing my new design;

FIG. 2 is a top view thereof;

FIG. 3 is a bottom view thereof;

FIG. 4 is a left side view thereof;

FIG. 5 is a right side view thereof;

FIG. 6 is a rear side view thereof; and,

FIG. 7 is a front side view thereof.

The contrast in stippling density between the center region and the remainder of the pet treat represents a contrast in color, and no particular colors are claimed.
